Patented Nov. 22, 1927.

UNITED STATES PATENT OFFICE.

CHARLES LESLIE MAITLAND, OF JASPER, ONTARIO, CANADA.

ELEVATING AND SUPPORTING BRACKET.

Application filed October 28, 1926. Serial No. 144,841.

This invention relates to improvements in elevating and supporting brackets and more particularly to brackets associated with silos and the like.

5 The objects of the invention are to provide a bracket of this description for elevating the loading pipes and retaining them in elevated position while a silo or the like is being loaded.

10 A further object is to provide a simple and durably constructed device operable from the ground for elevating and retaining in elevated position a pipe or the like.

15 Yet another object is to provide a device of this character that will overcome the trouble and necessity of climbing onto an object such as a silo to elevate the loading pipe and retain it in elevated position.

20 With these and other objects which will be hereafter more fully discussed in view, the invention, while illustrated in the accompanying drawings as used in connection with a silo, may be used under any other suitable conditions, consisting as it does of 25 a bracket member designed to be engaged by a pipe or the like and to fit snugly against the outside of an object such as a silo and provided with means for securing the bracket, and adjusting the same, and elevating mechanism operatively connected to the bracket and operable from the ground for hoisting the loading pipe to engage with the bracket.

25 Referring now to the drawings in which like characters of reference indicate corresponding parts in each figure,

30 Figure 1 is a perspective view of my improved supporting and elevating bracket.

35 Figure 2 is a side elevation partly in section of a wood silo fitted with my improved bracket, the loading pipe being indicated in dotted lines.

40 Figure 3 is a detail of the securing means for the bracket as illustrated in Figure 2.

45 Figure 4 is a modified form of securing the bracket in the case of a concrete silo.

50 In the drawings in which a preferred example of my invention is disclosed, 10 designates a silo on which is mounted my improved elevating and pipe retaining bracket comprising a frame 11 of substantially V-shaped formation, here shown as formed of a single length of iron bent to form the sides 12 and 13 and the curved end 14, the 55 wings or sides 12 and 13 being open at their inner ends and formed with spiked ends 15,

designed to engage the the outside of a silo. The sides are further connected with reinforcing cross-bars 16 and 17, while a centre longitudinally extending plate formed in two sections 18 and 19 adjustably connected to one another as at 20, is rigidly connected at one end to the end 14 of the frame and adapted at its inner end to lie snugly against the side of the silo. An additional bracing member 21 substantially V-shaped in formation is secured to the cross brace 16 and formed with a looped end adapted to register with the orifice 22 in the member 18, both of which are adapted to receive therethrough securing means, here shown in the form of screw-threaded bolts 23 with a protruding handle 24 designed to engage with a retaining plate 25 supported from the top of the silo and adapted to be secured to the bolt by a nut 26 formed thereon.

55 The plate 17 is rigidly secured to the sides 12 and 13, while the member 16 is pivotally mounted therein and connected to the supporting rod 21 previously mentioned, in turn rigidly connected to the outer end of the centre longitudinally extending section 18, so that the angle of the latter and the bracket as a whole can be readily adjusted so that with the means for adjusting the plate 19 as already described, the angle at which the bracket as a whole is to be set can also be readily adjusted.

60 A collar member 27 formed in two sections 28 and 29 hingedly connected to one another at 30, is provided on the front end of the bracket to engage with and support the loading pipe 31, provided with orificed laps 32 to retain the pipe securely in a vertical position. For lifting the pipe from the ground into engagement with the collar member on the bracket, I provide a link 33 secured to the frame and to which is connected a cable 34. This cable is adapted to extend over the pulley 35 on the pipe and the pulley 36 on the bracket 11.

65 In the modified form of securing the bracket to the silo in cases where it is built of stone or concrete and not readily adapted to have a hole drilled therethrough, I provide a suspension plate or bar 37 hooked at one end to engage with a link 38, in turn connected to the bracket and bent twice at right angles at the other end as at 39 to engage with the top of the silo.

70 From the foregoing it will be seen that my improved bracket is not only in itself,

adjustable, but that it can also be adjusted according to the length of the supporting plates 18 and 19. Furthermore in combination with the auxiliary collar, it can be 5 readily operated from the ground.

With my device, when it is required to elevate as in the present instance, a pipe of the silo, instead of several men getting up onto the silo and employing various means 10 for raising the pipe and securing the same, the auxiliary collar is first fitted thereon and then the cable 34 pulled to bring the pipe into substantially vertical position and in engagement with the collar member on 15 the bracket which is open and immediately closed on the pipe being inserted therein, and a pin 40 inserted thereby retaining the latter in a vertical position as indicated by the dotted lines in Figure 2. A bracket 20 may thus be fitted to a silo either by means of the screw-threaded key 23 and the plate 25, or as shown in Figure 4 by hooking it on the suspending plate 37 to the top of the silo.

25 As many changes could be made in the construction, and many apparently widely different embodiments of my invention, within the scope of the claims, constructed without departing from the spirit or scope 30 thereof, it is intended that all matter contained in the accompanying specification and drawings shall be interpreted as illustrative and not in a limiting sense.

What I claim as my invention is:

35 1. A supporting and elevating bracket comprising a frame, a centre plate formed in two sections adjustably connected to one another, one of said sections being rigidly

secured to the frame and the other section being associated with securing means for the frame, reinforcing rods pivotally carried by the frame and rigidly connected to the centre plate, a collar formed in two hingedly connected sections on the frame and means for locking the collar in closed 45 position.

2. A supporting and elevating bracket comprising a frame, a centre plate formed in two sections adjustably connected to one another, one of said sections being rigidly secured to the frame and the other section being associated with securing means for the frame, reinforcing rods pivotally carried by the frame and rigidly connected to the centre plate, a collar formed in two hingedly connected sections on the frame, means for locking the collar in closed position, an auxiliary engaging member, pulleys on the frame and a cable connected to the engaging member and travelling over 50 said pulleys whereby the engaging member is operable from the ground.

3. A supporting and elevating bracket comprising a frame, a plate formed in two sections adjustably connected to one another, one of said sections being rigidly secured to the frame and the other section being associated with securing means for the frame, reinforcing rods pivotally carried by the frame and rigidly connected to the plate, 55 a clamping member associated with the frame.

In witness whereof I have hereunto set my hand.

CHARLES LESLIE MAITLAND.
